No. 10,834.

PATENTED APR. 25, 1854.

W. M. STORM.
BULLET MOLD.

Inventor:

W. M. Storm.

is not in print.

UNITED STATES PATENT OFFICE.

WM. M. STORM, OF NEW YORK, N. Y.

IMPROVED BULLET-MOLD.

Specification forming part of Letters Patent No. 10,834, dated April 25, 1854.

To all whom it may concern:

Be it known that I, WM. MONTGOMERY STORM, of the city of New York, N. Y., have invented certain new and useful Improvements in Bullet-Molds, which render the operation of casting a ball more speedy and easy, while they at the same time provide more effectually for the delivery of a perfect ball than in any mold heretofore essayed; and I do hereby declare that the following specification, taken in connection with the drawings, is a full and clear description thereof.

Figure 1 of the drawings represents a perspective view of my bullet-mold complete; Fig. 2, a top view thereof when shut, and Fig. 3 a top view of the mold when open.

The amount of time consumed in casting a quantity of small balls and the greater space required for shaving off the sprues are facts well known to those who have essayed the task, and the worst feature of the whole operation is that the ball when completed is by no means perfect, as the operator, no matter how great his dexterity, invariably cuts off the sprue either too near the ball or too far from it. In either event the ball is no longer spherical, and its accuracy and range of flight are both impaired. Now, I am aware that these defects have been remedied entirely either by the process of producing balls by pressure or by cumbrous machinery, which furnishes the cast balls in large quantities in the course of a regular manufacture. Neither the process or the machine, however, will avail those who are, by the force of circumstances compelled to buy the lead and cast their own balls, and it is to suit the wants of this latter class that my mold has been devised.

To this end the nature of the first part of my invention consists in arranging the hinge, the jaws containing the mold proper, and the handles in such a manner that when combined with a spring said spring shall hold the two half-molds in contact and ready for the reception of the lead, and a grasp of one hand of the operator shall open the jaws and permit the bullet, when cast, to drop out; and the nature of the second part of my invention consists in combining with a bullet-mold a shaver in such a manner that by the action of one hand of the operator the cast bullet may be deprived of its sprue and the mold opened, so

as to permit the ball to drop, while a relaxation of his grasp causes the mold to close and the shaver and funnel to take such a position that the whole apparatus is ready for a new charge of lead.

In the bullet-mold as ordinarily constructed both hands are required even when casting and delivering a single ball, as the grasp of one hand closes the mold, while both hands—one on each handle—are required to open the matrix and release the ball. Much time is therefore lost in changing from one to both hands, and vice versa. Such a mold, even if provided with a cutter, would be but a poor contrivance, as, although it would increase the perfection of the ball, it would lessen only in a slight degree the time required in its formation. My mold, however, is so arranged that a strong grasp of one hand opens the matrix, while a relaxation of that grasp permits a spring to hold the two half-dies in sufficiently close contact to produce a good casting. This grasp of a single hand at the same time actuates the cutter or shaver and neatly removes the sprue. There also results from this arrangement the incidental and by no means slight advantage that the operator may retain continually in the other hand the vessel of molten lead until its contents are entirely molded into balls.

In the drawings, A A represent the arms of the mold; b b, the jaws, and c c the handles thereof. The two arms are pivoted to each other at e by a pin which passes through the projections on the one jaw and one on the other, forming a rule or compass joint. The arms are kept asunder and the jaws together by means of a spring, d, thus reversing the construction of the ordinary bullet-mold. In either jaw is accurately bored out a hemispherical cavity so located that the periphery of the spherical matrix, which they form when closed, is slightly cut by the plane which bounds the upper side of the jaws. One of these cavities is represented at k in the perspective view. Upon the upper side of these jaws is located the vibrating shaver and funnel f, pivoted upon one of the jaws and slotted near one of its extremities at h, while the other is reamed out at g, so as to form a small funnel, the reaming operation being pushed so far that a minute circular hole is bored en-

tirely through the shaver. This method of construction thins down the edges of this circular aperture, beveling it on all sides much in the same manner as the blades of shears. A small pin, *i*, projects from the other jaw and enters this slot, and the lengths of the two arms of the shaver, the position of its pivot, and the length of the slot are so calculated and adapted to each other that the minute hole in the shaver shall be immediately over the center of the cavity when the jaws are closed, and shall vibrate to one side when they are opened sufficiently far to completely sever the neck or sprue of the ball.

I will now proceed to describe the method of using the mold.

The apparatus in the position as represented in Fig. 2, which it naturally assumes, is held lightly in one hand, while the crucible of molten lead is grasped in the other. A small portion of lead is now poured into the funnel until the mold is filled. The handles are then tightly grasped by the hand that holds them, when the shaver cuts off the sprue. The mold is then slightly tapped against some solid body, and the finished ball and the sprue are both thrown out. The grasp of the operator is then relaxed, and the apparatus assumes its original position. Another charge of lead is poured in, and the operations are repeated in succession until the supply of lead gives out.

By reference to the drawings it will be perceived that the ball when cast and in the act of being deprived of its neck is by the action of the shaver held firmly against or rather in one of the hemispherical cavities, and that the top of its containing-jaw forms, with the shaver, a very effective shears.

It is obvious that the arrangement of the shears and the method of operating them by pins and slots or toggles or their equivalents may be varied in many ways without departing

from the principle of my invention so long as they are so constructed that a grasp of one hand of the operator opens the mold and shaves off the neck of the ball; and it is further evident that a series of molds might be formed in the jaws with a series of shavers properly arranged, or with one shaver for all the molds, and that such an arrangement would be a mere multiplication of my invention, and also that the spring might be riveted one leg to each jaw, with its bend extending as a nose beyond the jaws, in which case it would close the jaws by its tendency to contract, and that these and other arrangements of the spring or the use of springs of different well-known species would not alter the character of the invention so long as the spring always tends to hold the mold in the casting position.

Having thus fully described my invention, what I claim therein as new, and desire to secure by Letters Patent of the United States, is—

1. A hand bullet-mold so constructed that it may be forced open against the adhesion of the lead, so as to deliver its ball, by the pressing together of its handles by the strong grasp of a single hand, whereby are attained the important ends described.

2. In combination with a mold constructed as above described, the shears which are operated by the strong grasp of a single hand on the handles or their equivalents, whereby the ball is deprived of its sprue and released from its matrix by the closing or compressing together of the handles.

WM. MT. STORM.
